PUMP WITH FLEXIBLE IMPELLER AND FLEXIBLE ANNULAR CAM

Alan A. McCray, North Hollywood, Calif., assignor to Jabsco Pump Company, Burbank, Calif., a corporation of California

Application December 26, 1956, Serial No. 630,599

2 Claims. (Cl. 103—117)

The present invention relates in general to pumps and, more particularly, to a pump having an impeller provided with flexible radial vanes adapted to be flexed by a cam incorporated in the pump to produce the necessary pumping action, a primary object of the invention being to provide a pump having an improved cam for this purpose.

Still more particularly, the invention contemplates a flexible-vaned pump of the concentric type, the impeller in a pump of this type being mounted for rotation about the axis of a cylindrical impeller bore and the vane flexure necessary to achieve a pumping action being produced by a cam located in the impeller bore at one side thereof, between and overlapping the inlet and outlet ports of the pump. A pump of the concentric type has numerous advantages over a pump of the eccentric type, wherein the impeller is mounted for rotation about an axis spaced from and parallel to the axis of the impeller bore to achieve the necessary vane flexure, since all of the bores in the housing of a pump of the concentric type, including the impeller bore, bearing bores, and the like, are coaxial. However, the aforementioned cam required by the concentric type of pump to produce the necessary vane flexure has presented manufacturing difficulties prior to the present invention. Heretofore, flexible-vaned pumps of the concentric type have utilized a cam in the form of a machined insert mounted in the impeller bore at one side thereof between and overlapping the inlet and outlet ports, the angular or circumferential extent of such cam insert being considerably less than 180 degrees. Due to the fact that the radius of the internal peripheral wall of the cam varies circumferentially in the vicinities of the inlet and outlet ports to produce the desired vane flexure, machining such an insert in accordance with prior practice presents troublesome problems. For example, it is difficult to provide the internal wall of such a machined insert with a smooth contour for engagement by the blades or vanes of the impeller. It is also very difficult to provide the internal wall of such a machined cam insert with the contour necessary to produce smooth and quiet operation. These and various other difficulties encountered with machined cam inserts are eliminated by the present invention, which is an important feature thereof.

A fundamental object of the invention is to provide a cam for a flexible-vaned pump of the concentric type which merely comprises a flexible, sheet metal annulus inserted into the impeller bore and formed to provide the desired circumferentially varying internal radius in the vicinities of the inlet and outlet ports. Such a sheet metal annular cam may be die formed to provide the desired internal contour accurately and easily, which is an important feature of the invention. Since sheet metal stock is a relatively inexpensive starting material, and

2

since sheet metal stock may be die formed inexpensively, as compared to machining other stock, the present invention greatly reduces the cost of cams for flexible vanned pumps, which is an important feature.

5 Since the sheet metal annular cam is formed to provide the internal peripheral wall thereof with a reduced radius intermediate the inlet and outlet ports, the external peripheral wall of the annular cam is spaced inwardly from the peripheral wall of the impeller bore between the inlet and outlet ports. An important object of the invention is to secure the annular cam in place in the impeller bore by means of an elastomeric spacer block inserted between the external peripheral wall of the annular cam and the peripheral wall of the bore in the 10 region between the inlet and outlet ports, this elastomeric block being secured to the housing of the pump.

Another object is to provide a flexible, sheet metal annular cam in the form of a ring split at a point opposite the region of minimum internal radius, the annular 15 cam of the invention thus being similar to an ordinary split piston ring. The elastomeric spacer mentioned is located adjacent the region of minimum internal radius of the annular cam and serves to lock the annular cam in place in the annular bore with the longitudinal or longitudinal 20 extending ends of the split annular cam in abutment, thereby rendering the internal peripheral wall of the 25 annular cam a continuous annular surface.

An object in connection with one embodiment of the 30 invention is to provide a pump wherein the inlet and outlet ports in the housing are formed in the peripheral wall of the impeller bore and wherein the annular cam and the elastomeric spacer are provided with inlet and outlet ports respectively registering with the inlet and outlet 35 ports in the housing. With this construction, the elastomeric spacer mentioned serves as a sealing means for preventing fluid leakage between the inlet and outlet ports in the housing through the space between the external peripheral wall of the annular cam and the peripheral wall of the impeller bore, which is an important 40 feature.

An object in connection with another embodiment is to provide a pump wherein the inlet and outlet ports in the housing are formed in an end wall thereof, there being 45 no ports through the annular cam and the elastomeric spacer in this embodiment.

Another object is to circumferentially locate the inlet and outlet ports in either the peripheral wall of the housing or the end wall thereof at the vane-flexing ramps formed by the transitions between the minimum internal 50 radius of the annular cam and the maximum internal radius thereof.

The foregoing objects, advantages, features and results of the present invention, together with various other objects, advantages, features and results thereof which will be quite evident to those skilled in the pump art in the light of this disclosure, may be attained with the exemplary embodiments of the invention described in detail hereinafter and illustrated in the accompanying drawings, in which:

60 Fig. 1 is a transverse sectional view of a pump which embodies the invention;

Fig. 2 is an exploded perspective view of a flexible, sheet metal annular cam of the invention and of means of the invention for retaining the cam;

65 Fig. 3 is a side elevational view of another pump which embodies the invention; and

Fig. 4 is a transverse sectional view taken along the arrowed line 4—4 of Fig. 3.

Referring to Figs. 1 and 2 of the drawings, the numeral

10 designates a pump housing which is provided with a cylindrical impeller bore 12 and circumferentially spaced ports 14 and 16, the latter being formed in the peripheral wall 18 of the impeller bore in this embodiment. For the direction of impeller rotation hereinafter considered, the port 14 acts as an inlet port and the port 16 acts as an outlet port and the ports 14 and 16 will henceforth be termed inlet and outlet ports for convenience.

Within the impeller bore 12 is a flexible, sheet metal, annular cam 20 in the form of a split ring, the annular cam having longitudinal, i.e., longitudinally extending, ends 22 disposed in abutting relation. The annular cam 20 is provided with inlet and outlet ports 24 and 26 therethrough which register with the inlet and outlet ports 14 and 16, respectively. In the particular construction illustrated, the inlet and outlet ports 24 and 26 in the annular cam 20 are shown as simple circular ports, although they may have other configurations. For example, each of the ports 24 and 26 may comprise a plurality of circumferentially extending slots.

The annular cam 20 is provided with circumferentially extending segments 28 which are seated against the peripheral wall 18 of the impeller bore 12 and which have a maximum internal radius relative to the axis 30, equal to or slightly less than the radius of the pump impeller described hereinafter. The segments 28 of maximum internal radius extend circumferentially substantially throughout the major circumferential distance between the inlet and outlet ports 14 and 16. In the regions of the inlet and outlet ports 14 and 16 and in the region of the minor circumferential distance between these ports, the annular cam 20 is spaced from the peripheral wall 18 of the impeller bore 12. In the region of the minor circumferential distance between the inlet and outlet ports 14 and 16, the annular cam 20 provides a circumferentially extending segment 32 of minimum internal radius relative to the axis 30, the internal radius of the segment 32 preferably being constant throughout the region of the minor circumferential spacing between the ports. At the ports 24 and 26, the annular cam 20 is provided with circumferentially extending transitional segments or ramps 34 and 36 of radii varying circumferentially from the minimum adjacent the segment 32 to the maximum adjacent the segment 28. The configurations of the internal peripheral walls of the transitional segments 34 and 36 are such as to provide the entire internal peripheral wall of the annular cam with a smooth contour.

Disposed in the space between the housing 10 and the segments 32, 34 and 36, and engaging the peripheral wall 18 of the impeller bore 12 and the external peripheral walls of these segments, is an elastomeric spacer or block 38 having molded thereto a nut 40 to receive a screw 42 threaded through the housing 10, and having therein notches 64 and 66 registering with the ports 14 and 16, respectively, and with the ports 24 and 26, respectively. The elastomeric block 38 serves to retain the annular cam 20 in the impeller bore 12 in its proper position and closes any gap between the longitudinal ends 22 of the annular cam by bringing such ends into abutting relation. Also, in the embodiment under consideration, the elastomeric block 38 acts as a sealing means for preventing fluid leakage between the inlet and outlet ports 14 and 16 by way of the space between the housing 10 and the segment 32 of the cam. Thus, in this embodiment, the elastomeric block 38 performs the dual function of retaining the annular cam 20 and of providing a fluid-tight seal between the inlet and outlet ports 14 and 16, which is an important feature.

Mounted within the annular cam 20 for rotation about the axis 30 of the impeller bore 12 is an elastomeric impeller 44 having a hub 46 provided with flexible radial vanes or blades 48 engaging the internal peripheral wall of the annular cam. Molded into the hub 46 of the impeller 44 is an insert 50 which is telescoped over a shaft 52 and which is keyed thereto at 54.

As will be apparent, when the impeller 44 is rotated in the clockwise direction, the vanes 48 unflex as they move along the transitional segment 34 of the annular cam 20 into engagement with the segment 28 of maximum internal radius, thereby enlarging the intervane spaces to draw fluid thereinto through the inlet ports 14 and 24. As the vanes 48 move along the transitional segment 36 into engagement with the segment 32 of minimum radius, the vanes are flexed to decrease the volumes of the intervane spaces, thereby discharging fluid therefrom through the outlet ports 26 and 16.

As will be apparent, the annular cam 20 can be die formed readily and inexpensively from sheet metal stock, the cost of the cam 20 being much less than the cost of prior machined cams. Also, it is possible to provide the sheet metal cam 20 with a smooth internal contour designed for quiet operation. Further, since the cam 20 is an annulus, wear is confined to the cam and to the impeller 44, which elements can readily be replaced, there being no wear of the housing 10.

Referring now to Figs. 3 and 4, various components of the embodiment illustrated therein correspond to certain components of the embodiment of Figs. 1 and 2 and are designated by the same reference numerals plus "100." The embodiment of Figs. 3 and 4 differs in that the inlet and outlet ports 114 and 116 are located in an end wall 160 of the impeller bore 112, instead of in the peripheral wall 118 thereof, thereby making ports in the annular cam 120 and the elastomeric spacer 138 unnecessary. It is thought that the structure and operation of this embodiment will be apparent in the light of the description of the structure and operation of the embodiment of Figs. 1 and 2.

Although exemplary embodiments of the invention have been disclosed herein for purposes of illustration, it will be understood that various changes, modifications and substitutions may be incorporated therein without departing from the spirit of the invention as defined by the following claims.

I claim:

1. In a pump, the combination of: a housing provided with an impeller bore and provided with circumferentially spaced inlet and outlet ports in communication with said impeller bore; a flexible, preformed, annular cam lining and engaging the peripheral wall of said impeller bore and having a circumferentially varying internal radius relative to the axis of said bore, said internal radius being a minimum between said inlet and outlet ports and progressively increasing adjacent said inlet and outlet ports, there being a space between the external peripheral wall of said annular cam and the peripheral wall of said bore between and overlapping said inlet and outlet ports, the radial dimension of said space being a maximum between said inlet and outlet ports to provide said minimum internal radius therebetween and progressively decreasing adjacent said inlet and outlet ports to provide said progressively increasing internal radius there adjacent, said annular cam being a split cam having abuttable ends; an elastomeric spacer in said space and extending radially from the external peripheral wall of said annular cam to the peripheral wall of said impeller bore, said spacer providing a fluid-tight seal between said annular cam and the peripheral wall of said impeller bore between said inlet and outlet ports and holding the abuttable ends of said annular cam in abutting relation; and an impeller with flexible vanes mounted for rotation within said annular cam about the axis of said bore, said flexible vanes engaging the internal peripheral wall of said annular cam.

2. A pump as set forth in claim 1 wherein said abuttable ends of said annular cam which are held in abutting relation by said spacer are diametrically opposite said spacer.
